UNITED STATES PATENT OFFICE.

THOMAS NOBLE, OF ST. ANNES ON THE SEA, ENGLAND.

RAILWAY-CHAIR.

No. 818,391.

Specification of Letters Patent.

Patented April 17, 1906.

Application filed January 19, 1906. Serial No. 296,835.

To all whom it may concern:

Be it known that I, THOMAS NOBLE, a subject of the King of Great Britain, residing at St. Annes on the Sea, in the county of Lancaster, in the Kingdom of England, have invented certain new and useful Improvements in Railway-Chairs, (for which application has been made in Great Britain, No. 26,294, dated December 16, 1905,) of which the following is a specification.

This invention has for its object an arrangement of railway-chair whereby a half-round sleeper can be used instead of a rectangular one. By this means two sleepers can be made by simply splitting or sawing a round log of the requisite size into two, or into two with a central slab for other use, and then slightly squaring the edges.

In the accompanying drawings, Figure 1 is an end view of my railway-chair in cast metal applied to a sleeper or tie rounded on the top face; Fig. 2, a side view thereof; Figs. 3 and 4, end views of my chair in wrought iron or steel applied, respectively, to flat-bottomed and double-headed rails.

Referring first to Figs. 1 and 2, A is the half-round sleeper or tie; B, the chair. The chair B is made with a base B', the under side of which is of concave shape or made in the shape of the segment of a circle, so as to fit onto the half-round sleeper A. The upper surface of the chair B is of the ordinary type—namely, it is made with two jaws C to receive the double-headed rail D, with a wood

key E between the web of the rail D and the adjacent jaw. If the chair be cast, the jaws C are cast in one with the base B'. In use the chair need only be bedded onto the sleeper and the spikes or dogs F driven in.

Where it is made of wrought-iron or wrought-steel, a part of the base B' can have slits cut in it, and the tongues G, thus formed, turned up, so as to form a jaw between which the rail D is fixed, as shown in Fig. 4. These tongues G, however, in flat-bottomed rails can be hammered down onto the flanges of the rail D to hold it tight, as shown in Fig. 3, and dogs H pass through the hammered-down flanges and through the rail D into the

50 sleeper to hold the same tight, other dogs F holding the base of the chair tight on its sleeper. The spikes or dogs are driven into the sleeper radially to the curvature of the

base of the chair and of the sleeper itself, and they thus hold against a vertical up-and-down shaking very much better than those spikes which are driven vertically downward. The other advantages of this chair are, first, great economy in timber; second, the chair will still hold on the sleeper even if the spikes 60 get loose; third, there is much less danger of the sleeper cracking under pressure of the driven spikes or dogs; fourth, the sleeper itself having its bottom flat and its top round holds in the ground better than a rectangular 65 sleeper does, as it is to a certain extent dove-tailed into the ground, and, fifth, water drains off a rounded sleeper very much quicker than off a flat sleeper or a sleeper even slightly 70 concave at the top, as there is no flat or hollow space for water to lodge in.

By my invention the necessity of providing a flat place in round-topped sleepers, truly adzed and planed as a seating for flat-bottomed chairs, is dispensed with. My chairs 75 seat themselves on the sleeper without any such flat place being provided and provide a large bearing-surface of considerably greater area than the ordinary chairs.

I declare that what I claim is—

1. In combination with a rail, and a tie or sleeper having a rounded top surface, of a chair or support provided with jaws to receive the rail, a base so shaped as to fit the contour of and seat itself on the tie or sleeper, 85 and fastening means for fastening the chair to the sleeper radially to the curvature of the base of the chair and of the sleeper itself.

2. In combination with a rail, and a tie or sleeper having a rounded top surface, of a 90 chair or support having a base cast in one piece with the jaws, said base being made concave on its under side to fit and seat itself on the rounded top surface of the sleeper.

3. In combination with a rail, and a tie or 95 sleeper having a rounded top surface, of a chair or support having a base shaped to fit and seat itself on the rounded top surface of the tie or sleeper, a slit cut in said base and the tongue thus formed turned up so as to 100 form a jaw against which the rail is fixed, and means for fastening the rail to the chair, and the chair to the sleeper.

4. In combination with a rail, and a tie or 105 sleeper having a rounded top surface, of a chair or support having a base shaped to fit

and seat itself on the rounded top surface of the tie or sleeper, a slit cut in said base and the tongue thus formed bent over and hammered down onto the flange of the rail to hold it tight, and a dog or spike passed through the hammered-down flange and through the rail and the sleeper to hold same tight.

In witness whereof I have hereunto signed my name, this 8th day of January, 1906, in the presence of two subscribing witnesses.

THOMAS NOBLE.
